[57] CLAIM

The ornamental design for a vehicle wheel chock, substantially as shown and described.

DESCRIPTION

FIG. 1 is an isometric view of a vehicle wheel chock showing my new design.

FIG. 2 is a top plan view thereof.

FIG. 3 is a side elevational view thereof, the opposite side being a mirror image of the side shown therein.

FIG. 4 is a front elevational view thereof; and

FIG. 5 is a rear elevational view thereof.

The bottom of the vehicle wheel chock is substantially flat and unornamented.
